UNITED STATES PATENT OFFICE.

GORDON F. DODGE, OF CHICAGO, ILLINOIS.

METAL REINFORCE FOR CONCRETE.

No. 909,850.

Specification of Letters Patent.

Patented Jan. 12, 1909.

Application filed July 8, 1908. Serial No. 442,611.

To all whom it may concern:

Be it known that I, GORDON F. DODGE, a citizen of the United States, residing in Chicago, in the county of Cook and State of Illinois, have invented a new and useful Improvement in Metal Reinforces for Concrete, of which the following is a specification.

This invention relates to metal reinforcing devices for use in concrete and similar structures, and more especially to that class of reinforce devices embodying rigid main members or bars and supplemental members attached to the bars and adapted to engage and lock with the concrete at a distance from the bars, whereby the cracking of the material and its separation from the bars is prevented. The main bar, has in some cases, been formed integral with a section of expanded metal forming the supplemental member of the reinforce, but more generally this bar has been of rolled metal, either flat, angle or T iron made separate from and secured to the supplemental member or web by riveting. In some cases also the main bar has been provided with a longitudinal groove or channel, in which some portion of the supplemental member has been inserted and secured by pinching together the sides of the grooves or channel in such manner as to impinge upon or partially inclose the supplemental member. My invention is an improvement upon these constructions in several important respects, as it provides for a, large range of adjustment in the matter of strength with very little change in size, and permits the making of the bar from mild or medium steel. Its nature is fully disclosed below and will be fully understood from the accompanying drawings, in which:

Figure 1 is an elevation of a preferred form of the invention; Fig. 2 is a section on line 2—2 of Fig. 1; Figs. 3 and 4 are perspectives of a portion of the bar forming a part of the main member, showing its opposite sides; Fig. 5 is a view similar to Fig. 1 of a modified construction; Fig. 6 is a section on line 6—6 of Fig. 5; Fig. 7 is a perspective of the bar, and Fig. 8 is a like view showing one manner of using the reinforce in the construction of columns. Figs. 9 and 10 are perspective views of different constructions of the bars comprising the principal member of the reinforce. Figs. 11 and 12 show modifications.

In Figs. 1 to 4, inclusive, the bars compos-

ing the principal member are shown at 11. Such bars are essentially alike, and made in continuous lengths and each is substantially flat and preferably flanged on one side as at 12, and also provided on the same side with transverse ribs or ridges 13, or other projections intended to establish mechanical bonds with the concrete. Upon the other side face, each bar is provided at proper intervals with lugs 14, intended to serve as a means for engaging the supplemental member 15 whether the same be in the form of stirrups, or expanded metal. The lugs are preferably elliptical in form, or in any event are rounded on the side engaging the supplemental members. Two of these bars 11 are placed together with the sides carrying the lugs face to face, to form the principal member of the invention, and the supplemental member or web is secured therein by being placed with the lugs of the bars entered in its loops or meshes, as is plainly shown in Fig. 1. The two bars 11 may be secured together in any suitable way, but I prefer to effect this by means of strong clips 16 passing around the outside of the bars, as shown in Figs. 1 and 2, as by that means of fastening the two bars are made to form practically a unit, and are not weakened in any way by cutting away the metal or forming rivet or bolt holes.

The bars are desirably formed with the web engaging lugs along both edges as shown, as thereby a supplemental member may be attached at either edge or both edges. The united bars thus provided with supplemental members at both edges are specially adapted to be used as a reinforce in slab work.

In the modified construction shown in Fig. 5 and subsequent figures, is the provision on the abutting faces of the two rigid member bars 11 of the longitudinal ridges 17, the lugs 14 for locking the supplemental members 15 being formed above and below the ridges, as plainly seen at Fig. 7. The bars of this construction are fastened together by clips 16 in the manner described in connection with the main figures, and they are also adapted to be secured to supplemental members at either edge or both edges, and shown as so secured in Figs. 5 and 6. The bar of this modified construction is shown as provided with bonds 15 for mechanical engagement with the concrete, as shown in Figs. 9 and 10.

in vertical position as in column work, and having a clip 18 uniting them to a band 19 surrounding the column, the clip being secured upon the lugs 14 of the bars. These 5 bars are fastened together in pairs by clips 16 similar to that employed in the other figures. Two or more of the principal members may be arranged for compression reinforcement with supplemental members attached to the two edges to preserve intervals 10 and provide for mutual action, as for example in columns and struts. See Figs. 11 and 12. If the strength of the supplemental member should not be as great as desired, 15 that member may be supplemented by stirrups 20 secured between the bars and upon the lugs thereof, as seen at Fig. 1.

The invention permits the combining in one reinforce of bars differing in thickness, 20 so that the principal member may be made to have any desired strength, and by keeping the bars in stock in a variety of sizes, they may be assembled as needed for the place of use.

25 I claim:

1. The combination with the body of concrete, of a metal reinforce therefor, consisting of a rigid main member composed of two separate parallel bars arranged side by side with their faces abutting, said faces having a plurality of projecting lugs for engaging a supplemental member at separated points, and a supplemental member engaged by said lugs.

30 2. The combination with a body of concrete, of a metal reinforce therefor, such reinforce consisting of a rigid main member composed of two parallel separate continu-

ous bars arranged side by side with their faces abutting, said faces having projecting 40 lugs for engaging a supplemental member, and said supplemental member engaged by said lugs, said bars being suitably fastened together so as to confine the supplemental member on the lugs. 45

3. The combination with a body of concrete, of a metal reinforce therefor, such reinforce consisting of a main rigid member composed of two parallel separate continuous bars arranged side by side with their 50 faces abutting, said faces having projecting lugs for engaging a supplemental member, and said supplemental member engaged by said lugs, said bars being fastened together by clips so as to confine the supplemental 55 member on the lugs.

4. The metal reinforce for concrete, consisting of two main rigid bars of rolled metal arranged side by side with their faces abutting, said faces having a plurality of 60 projecting lugs for engaging a supplemental member at separate points in combination with a supplemental member engaged by said lugs.

5. The metal reinforce for concrete where- 65 in are combined two parallel and separate rigid bars forming the main member of the reinforce, said bars being arranged side by side and having a plurality of lugs on their abutting faces whereby to engage a supplemental member at separated points, and 70 means for securing said bars together.

GORDON F. DODGE.
